UNITED STATES PATENT OFFICE.

OLOF J. LOFQUIST, OF GRAND RAPIDS, MICHIGAN.

LINE APPLIANCE.

1,215,391.

Specification of Letters Patent. Patented Feb. 13, 1917.

Application filed March 4, 1916. Serial No. 82,219.

To all whom it may concern:

Be it known that I, OLOF J. LOFQUIST, a citizen of the United States of America, residing at Grand Rapids, in the county of Kent and State of Michigan, have invented certain new and useful Improvements in Line Appliances; and I do hereby declare the following to be a full, clear, and exact description of the invention, such as will enable others skilled in the art to which it appertains to make and use the same.

This invention relates to a device especially adapted for use in the tightening or taking up of the slack in lines which are stretched between two points such for instance, as clothes lines. It is the object and purpose of my invention to provide a device of this character which may be quickly and easily applied to the line and through a simple operation effect the tightening of the line to any desired degree of tension. A further object of the invention consists in the production of a novel means for retaining the device on the line when it is not in use so that it will not become lost and will always be in position to serve its purpose. Various other objects and purposes together with novel details of construction will appear as the description progresses of the preferred embodiment of the invention shown in the accompanying drawing, in which;

Figure 1 is an elevation showing the application of the device to a line.

Fig. 2 is a plan view; and

Fig. 3 is a view similar to Fig. 1 but taken from the opposite side.

Like reference characters refer to like parts throughout the several views of the drawing.

In the construction as shown there is provided a drum 1 having a circumferential groove between the flanges 2 and 3, the latter flange being wider than flange 2 so that it may be cut to provide a slot to receive the end of a handle 4 which is permanently attached to the drum in any suitable manner. Adjacent its free end and at one edge the handle has a diagonal notch 5 cut therein and between the notch and the drum a pin 6 projects from the handle in the same direction as the projection of the drum from the handle.

The drum also has a diametrically disposed slot cut in it as indicated at 7, said slot passing through the flange 2 and substantially to the center of said drum. A

member 8 of spring material is attached at one end to the drum at one side of the slot and extends thereover, its free end 9 passing a distance beyond the flange 2 as shown in Figs. 2 and 3. It will also be noted that the location of the slot 7 is at right angles to that of the handle 4.

In practice, the implement just described is applied to a line which is loose or slack between its points of attachment, this line being indicated at 10, the spring member 9 moving outwardly sufficient that the line is received within the slot 7. The application to the line is readily accomplished by merely hooking the end 9 of the spring member thereover and applying force to the handle such that the spring member 8 moves away from the face of the drum sufficient to permit the passage of the line to the slot. The handle is then grasped and turned through an arc of a circle sufficient that it comes substantially parallel to the length of the line. This will occur when a quarter turn has been given. It will again occur upon a three-quarters turn and thereafter with every additional half turn. When enough of the slack has been taken up by the winding of the line around the drum 1 the handle is brought adjacent the line and it is carried through the diagonal slot 5 either over or under the pin 6 as may be desired, this pin being of utility to hold the line within the slot especially when in the position indicated in dotted lines in Fig. 3.

By reason of the retaining member, when the line is unwound the device is held upon the line and does not become lost. In practice, especially with a clothes line, it is desirable that when not in use it shall be slackened but when it is in use this slack should be taken up. Between the times when it is in use the device shown will be merely retained on the line ready at any time to serve its function.

I claim:

1. In a device of the character described, a drum provided with a circumferential groove and with a diametrically disposed slot in one face, a handle attached to the opposite face of the drum, said handle having a diagonally disposed slot in one edge adjacent its free end, and a pin projecting from the handle, in the same direction as the drum and located between the drum and the slot in the handle.
2. In a device of the character described,

a drum provided with a circumferential groove and with a slot in one face, a handle secured to the opposite face of the drum, said handle having a slot adjacent its free end, and a spring retaining member attached at one end to the drum, extending across the slot therein and having its free end extending beyond the edge of the drum.

3. In a device of the character described, 10 a drum provided with a circumferential groove and a diametrically disposed slot in one face, a handle secured to the opposite

face of the drum, said handle having a diagonally disposed slot in one edge adjacent the free end of the handle, a pin projecting 15 from the handle in the same direction as the drum and between the drum and the slot in the handle, and a spring retaining member attached at one end to the drum, passing across the slot in the drum and having its 20 free end extending beyond the edge of the drum.

In testimony whereof I affix my signature.
OLOF J. LOFQUIST.
